STOKER CONSTRUCTION

Royce L. Beers, Detroit, Mich., assignor to Detroit Stoker Company, Detroit, Mich., a corporation of Michigan

Application October 10, 1932, Serial No. 637,186
Renewed May 8, 1936

23 Claims. (Cl. 110—115)

This invention relates generally to stokers of the sprinkler type and consists of certain novel features of construction, combinations and arrangements of parts, that will be hereinafter 5 more fully described and particularly pointed out in the appended claims.

In the accompanying drawings:

Figure 1 is a vertical sectional view through a furnace and showing stoker mechanism embodying my invention applied thereto;

Figure 2 is a sectional view taken on the line 2—2 of Figure 1;

Figure 3 is a sectional view taken on the line 3—3 of Figure 1;

Figure 4 is a sectional view taken on the line 4—4 of Figure 1;

Figure 5 is a sectional view taken on the line 5—5 of Figure 2;

Figure 6 is a detail view of the rotor drum;

Figure 7 is a sectional view taken on the line 7—7 of Figure 6;

Figure 8 is a detail view of one of the baffles;

Figure 9 is a detail view of the base plate;

Figure 10 is a detail view of one of the side 25 plates;

Figure 11 is a detail view of the other side plate;

Figure 12 is a detail view of one of the air ducts to the apron tuyères.

Referring now to the drawings wherein I have illustrated one embodiment of my invention, A is the front plate; B is the base plate; C and D respectively are the side plates; E and F respectively are the front and rear cross plates; and G is the cover plate.

H are baffles for the side plates; I is a shaft journaled in bearings J carried by the side plates; K is a rotor drum fixed upon the shaft I between the baffles H; and L are blades fixed to the drum K. M is a pan projecting forwardly from the base plate B at the lower edge I of the opening 2 therein and having a curved bottom 3 substantially coaxial with the shaft I, and N is a curved plate secured upon and cooperating with the curved bottom of the pan to form a housing for the rotor drum K. In this connection it will be noted that the plate N and pan M are bolted together and that the pan detachably engages the base plate B, hence the pan may be readily removed when desired to afford access to and replacement of the blades L.

O is a hopper for green fuel mounted upon the plates C, D, E and F; P is an adjustable plate over which the green fuel from the hopper may

be advanced by a suitable ram or feed plate Q so that such fuel will be fed onto and will be projected rearwardly in spray form by the blades L on the rotating drum K.

R are deflector plate sections extending upwardly and rearwardly from the rear edge of the rear cross plate F to the upper edge 5 of the opening 6 in the front plate A; S is an apron extending downwardly and rearwardly from the lower edge 1 of the opening 2 in the base plate 10 B; and T is a supporting plate for the apron. U is the dead plate and V are air ducts carried by said dead plate for conducting air from the wind chamber W to the space 10 between the supporting plate T and apron S. Preferably the 15 apron S comprises a series of tuyère blocks 11 arranged side by side and having inlet and outlet openings 12, 13 and 14 respectively for air, and the pan M is provided at opposite ends thereof with rearwardly extending ducts 15 and 16 20 for air from the space 10. In order that such air may be used to cool the bearings J and assist in the combustion of fuel within the furnace, the baffles H for the side plates are provided with passages 17 and 18 respectively that 25 are adapted to receive air from the ducts 15 and 16 in the pan and to discharge it into the furnace just below the deflector sections R. In this connection it will also be noted that the rotor drum K is hollow and is provided with openings 30 19 and 20 respectively. Preferably the openings 19 are of the keyhole type and are adapted to receive suitable bolts 21 constituting anchorage means for the blades L. However, when the parts are assembled the bolts are secured in the restricted or narrow parts of the openings 19. Preferably the bases 22 of the blades L are recessed as at 23 for registering with the larger parts of the openings 19 and have lateral outlet 35 passages 24 for said air. Consequently the air from the ducts 15 and 16 will be drawn through the openings 20 in the ends of the drum and will flow through the drum and out through the openings 19, recesses 23 and passages 24 to the space about the drum in the housing therefor.

As a result the rotor drum is air cooled. Due to the rotation of the drum and the configuration of the pan M and drum housing the air is admitted at high velocity so that fine particles of the fuel are blown into the furnace and are prevented from settling at the front end of the grates X. Thus this air serves both the purpose of combustion and distribution of the fine fuel.

In use, the fuel from the hopper O will be

moved by the ram Q rearwardly on the plate P so that it will fall upon and be projected rearwardly in the furnace by the blades L on the rotating drum K. Once within the furnace the fine fuel is burned in suspension and the coarse fuel is burned on the grates X. The apron S catches the fine material, dust, etc. However, such apron is cooled by the air from the space 10, hence will not burn out. Preferably the air 10 is supplied to the wind chamber W by a blower or fan (not shown), consequently the proper passage of air through the ducts V, apron sections 11, ducts 15 and 16, rotor drum K and passages 17 and 18 will be provided while the stoker is 15 in operation.

What I claim as my invention is:

1. In a stoker, an upright plate attachable to the front of a furnace and having an opening therein through which fuel may be propelled into 20 the furnace, a rotor housing in front of said plate and discharging rearwardly through said opening, a chamber for air in rear of said plate just below said opening, the top of said chamber being inclined downwardly and rearwardly and 25 forming an apron for said opening, said apron having means for conducting air from the chamber rearwardly into the furnace and forwardly through the opening aforesaid into the housing, and means for conducting air from the chamber 30 forwardly beneath the opening into the housing.

2. In a stoker, an upright plate attachable to the front of a furnace and having an opening through which fuel may be propelled into the furnace, a rotor housing in front of said plate 35 and discharging rearwardly through said opening, a rotor within said housing for propelling fuel through the opening, a chamber for air in rear of said plate just below said opening, and means for conducting air to said chamber, the 40 top of the chamber inclining downwardly and rearwardly from the lower edge of the opening in the upright plate aforesaid and comprising a series of tuyère blocks arranged side by side and having means for conducting air from the 45 chamber into the rotor housing.

3. In a stoker, an upright plate attachable to the front of a furnace and having an opening therein through which fuel may be propelled into the furnace, a rotor housing in front of said plate 50 and discharging through said opening, a rotor within said housing adapted to propel fuel through said opening, a chamber for air in rear of said plate just below said opening, the top of said chamber inclining downwardly and rearwardly from the lower edge of said opening and forming an apron for fuel propelled through the opening, means for conducting air to said chamber, and means for conducting air from the chamber into said rotor housing.

4. In a stoker, an upright plate attachable to the front of a furnace and having an opening therein through which fuel may be propelled into the furnace, a rotor housing upon the front of the plate and discharging through said opening, 60 a rotor within said housing adapted to propel fuel through said opening, and a chamber for air upon the rear of the plate just below the opening, the top of said chamber inclining downwardly and rearwardly from said opening and forming an apron for fuel propelled into the opening, and the bottom of said housing having a rearwardly projecting air duct extending into and adapted to receive air from the air 65 chamber aforesaid.

5. In a stoker, an upright plate attachable to the front of a furnace and having an opening through which fuel may be propelled into the furnace, a rotor housing projecting forwardly from said plate and discharging through said 5 opening, a rotor within the housing adapted to propel fuel through the opening, an air chamber in rear of said plate just beneath said opening, a dead plate in rear of said upright plate beneath the air chamber, means extending through the 10 dead plate and conducting air to the chamber, and means for conducting air from the chamber to the interior of the rotor housing.

6. In a stoker, an upright plate attachable to the front of a furnace and having an opening 15 through which fuel may be propelled into the furnace, a rotor housing in front of the plate discharging into said opening, a rotor within the housing adapted to propel fuel through the opening, and an apron inclining downwardly and 20 rearwardly from the lower edge of the opening aforesaid, said apron comprising a series of elongated tuyère blocks arranged side by side, said blocks being provided in adjacent edges at their lower ends with outlets for air, provided at their 25 upper forward ends with outlets for air, and having passages for air extending longitudinally thereof between said first and last mentioned outlets, the lower walls of said passages being interrupted intermediate of their ends for the 30 reception of air.

7. In a stoker, a hollow rotor having a passage for air extending radially thereof from its interior to its periphery, a blade mounted on the periphery of the rotor having a recess opening 35 toward the periphery and cooperating therewith to form a chamber for air, said chamber being in communication with the radially extending passage aforesaid and having an outlet passage adjacent the periphery of said rotor. 40

8. In a stoker, an upright plate attachable to the front of a furnace and having an opening therein through which fuel may be propelled into the furnace, a rotor housing projecting forwardly from said plate and discharging rearwardly 45 through said opening, a chamber for air projecting rearwardly from said plate beneath the fuel opening therein, the top of said chamber inclining downwardly and rearwardly from the lower edge of said opening and constituting an apron, 50 said inclined top being provided with means for discharging air rearwardly into the furnace, and means for conducting air from the chamber forwardly beneath the fuel opening aforesaid to the interior of said housing, to be propelled with 55 fuel rearwardly through said openings.

9. In a stoker, an upright plate attachable to the front of a furnace and having an opening therein through which fuel may be projected into the furnace, a rotor housing projecting forwardly from said plate and discharging rearwardly through said opening, said housing having side plates and being provided at the bottom thereof with air inlets, a rotor shaft within said housing and extending through said side plates, 65 bearings for said shaft mounted upon the outer sides of said plates, and baffle plates upon the inner sides of said side plates, said baffle plates being substantially parallel to said side plates and having flanges projecting laterally therefrom toward and cooperating with the side plates to form passages for air leading from the inlets aforesaid toward the opening in the upright plate adjacent the bearings. 70

10. In a stoker, a rotor housing having side plates, a rotor shaft within said housing and extending through said plates, bearings for said shaft mounted upon the outer sides of said plates, 5 baffle plates mounted upon the inner sides of and substantially parallel to said side plates, said baffle plates having flanges projecting laterally therefrom toward and cooperating with the side plates to form air passages adjacent the bearings for cooling purposes, said baffle plates having openings receiving said shaft, a hollow substantially cylindrical blade carrying rotor having ends fixed to said shaft and disposed within the openings in said baffle plates, the ends of said 10 rotor having air passages establishing communication between the interior of the hollow rotor and the air passages aforesaid.
11. In a stoker, an upright plate attachable to the front of a furnace and having an opening 20 therein through which fuel may be propelled into the furnace, a rotor housing projecting forwardly from said plate and discharging through said opening, said housing having a pair of side plates and provided at the bottom thereof upon the inner sides of said side plates with air inlets, and baffle plates upon the inner sides of and substantially parallel to said side plates, said baffle plates having flanges projecting laterally therefrom toward and cooperating with the side plates to 25 form air passages leading from the inlets aforesaid toward the opening in said upright plate.
12. In a stoker, a rotor drum having connecting axially and radially extending passages for air, blades having bases upon the periphery of the drum, said bases having recesses opening toward and cooperating with the periphery of said drum to form air chambers in communication with said radially extending passages, said chambers having air outlets adjacent the periphery of said 30 drum, and securing means for the blades extending through said bases and said radially extending passages.
13. In a stoker, an upright plate attachable to the front of a furnace and having an opening 45 therein through which fuel may be propelled into the furnace, a rotor housing in front of said plate and discharging rearwardly through said opening, and a chamber for air in rear of said plate just below said opening, the top of said chamber being inclined downwardly and rearwardly and 50 forming an apron for said opening, said apron having means for conducting air from the chamber rearwardly into the furnace and forwardly through the opening aforesaid into the housing.
14. In a stoker, an upright plate attachable to the front of a furnace and having an opening 55 therein through which fuel may be propelled into the furnace, a rotor housing projecting forwardly from said upright plate and discharging rearwardly through said opening, and apron tuyères inclining downwardly and rearwardly from the lower edge of the opening in said upright plate, said tuyères having means for discharging air rearwardly into the furnace and 60 other means for conducting air forwardly through the opening aforesaid into said housing to be propelled with fuel rearwardly through said opening.
15. In a stoker, an upright plate attachable 65 to the front of a furnace and having an opening therein through which fuel may be propelled into the furnace, a chamber for air upon the rear side of said upright plate beneath said opening, said chamber having means for discharging air rearwardly into the furnace, a rotor housing project- 70
- ing forwardly from said upright plate and discharging rearwardly through said opening, and means for conducting air from the chamber beneath the opening to the interior of said housing to be propelled with fuel rearwardly through 5 said opening.
16. In a stoker, an upright plate attachable to the front of a furnace and having an opening therein through which fuel may be projected into the furnace, a substantially trough-shaped 10 housing projecting forwardly from said plate and discharging through said opening, said housing being provided at the bottom thereof with means for receiving air from a point in rear of the upright plate, said housing having side plates and 15 baffle plates mounted upon and substantially parallel to said side plates, said baffle plates having flanges projecting laterally therefrom toward and cooperating with the side plates of the housing to form passages for conducting air from the receiving means aforesaid toward the opening in 20 said upright plate.
17. In a stoker, an upright plate attachable to the front of a furnace and having an opening therein through which fuel may be projected into 25 the furnace, a rotatable blade-carrying drum in front of said plate adjacent the opening therein, a housing for the drum projecting forwardly from said plate and discharging through said opening, said housing having side plates, bearings carried by the side plates of said housing, a shaft for said drum journaled in said bearings, baffle plates substantially parallel to the side plates of said housing, said baffle plates having semi-circular openings receiving the drum and cooperating 30 with the side plates of the housing to provide therebetween passages for air extending from points adjacent the bottom of the housing to points adjacent the opening in the upright plate, and means associated with said housing for conducting air to said passages.
18. In a stoker, an upright plate attachable to the front of a furnace and having an opening 35 therein through which fuel may be propelled into the furnace, a substantially trough-shaped housing projecting forwardly from said plate and discharging rearwardly through said opening, said housing having side plates and being provided at the bottom, thereof with inlets for air bearings carried by the side plates of said housing, a shaft 40 journaled in said bearings, a blade-carrying drum sleeved upon and rigid with said shaft between the side plates of said housing, and means associated with the side plates of said housing for conducting air from said inlets at the bottom of 45 the housing past the bearings toward the opening in said upright plate.
19. In a stoker, an upright plate attachable to the front of a furnace and having an opening 50 therein through which fuel may be propelled into the furnace, a rotor housing in front of said plate and discharging rearwardly through said opening, a chamber for air in rear of said plate just below said opening, said chamber having means for discharging air rearwardly into the furnace, 55 and means for conducting air from the chamber forwardly beneath the opening into the housing.
20. In a stoker, an upright plate attachable to the front of a furnace and having an opening 60 therein through which fuel may be propelled into the furnace, a rotor housing in front of said plate and discharging rearwardly through said opening, a chamber for air in rear of said plate below said opening, and two means for conducting air from said chamber forwardly into the rotor 65
- 75

housing to be propelled with fuel rearwardly through the opening in said plate, one of said means extending through said opening and discharging toward the bottom of the rotor housing, 5 and the other of said means being beneath said opening and discharging upon the bottom of the rotor housing.

21. In a stoker, an upright plate attachable to the front of a furnace and having an opening 10 through which fuel may be propelled into the furnace, a rotor housing in front of said plate and discharging rearwardly through said opening, a rotor within said housing for propelling fuel through the opening, a chamber for air in rear 15 of said plate just below said opening, and means for conducting air to said chamber, the top of the chamber inclining downwardly and rearwardly from the lower edge of the opening in the upright plate aforesaid and comprising a series of tuyère 20 blocks arranged side by side and having means for conducting air from the chamber directly into the furnace.

22. In a stoker of the sprinkler type, an upright plate having an opening therein through 25 which fuel may be propelled into the furnace, a rotary impeller housing in front of said plate ar-

ranged to discharge over the lower edge of said opening, a rotary impeller within said housing, an apron inclining rearwardly and downwardly from the lower edge of said opening and having air discharge passages at its lower edge, and means for 5 discharging air rearwardly through said passages from the lower rear edge of said apron.

23. In a stoker of the sprinkler type, a furnace front including an upright plate having an opening therein through which fuel may be propelled 10 into the furnace, a rotary impeller housing in front of said plate arranged to discharge over the lower edge of said opening, a rotary impeller in said housing, a stationary member extending rearwardly from said furnace front, a grate in 15 rear of said stationary member, an apron above said stationary member inclining rearwardly and downwardly from the lower edge of said opening and having air discharge passages at its lower edge, and means for discharging air rearwardly 20 through said passages from the lower rear edge of said apron whereby any dust and fine particles of fuel deposited on said apron and discharging from the rear end thereof will be carried by said air current rearward and over the grate. 25

ROYCE L. BEERS.
